UNITED STATES PATENT OFFICE

2,473,823

METHOD OF AND APPARATUS FOR
FINISHING GARMENTS

Robert E. Sands, Philadelphia, Pa.

Application March 12, 1945, Serial No. 582,247

12 Claims. (Cl. 34--12)

1

This invention relates to methods of and apparatus for finishing garments and the like.

The principal object of the present invention is to provide a method and means for finishing garments whereby a large plurality of garments may be simultaneously finished, eliminating the individual pressing of the same, and thereby effecting large savings of labor.

A further object of the invention is to provide a method and means for finishing garments whereby the same will be more efficiently and satisfactorily finished, and gloss or shine caused by pressing in the usual manner will be avoided.

With the foregoing objects in view my invention contemplates the provision of a cabinet having an interior chamber in which large numbers of garments are subjected to the action of expanding steam, which will serve to distend the garments and subject the fabrics thereof to the action of the steam; and in which thereafter said garments are subjected to the action of heated dry air without removing the same from the chamber so that any moisture which may be left in the garment through the condensation of the steam will be quickly removed before the same will improperly act on the garment.

The nature and characteristic features of the invention will be more readily understood from the following description taken in connection with the accompanying drawing, forming part hereof, in which:

Figure 1 is a side elevation of apparatus embodying the main features of the invention and for carrying out the method thereof, certain portions being broken away to illustrate the interior construction and arrangement;

Fig. 2 is a similar view, in end elevation, of the apparatus shown in Fig. 1, a portion of the door provided in the end of the structure being broken away to illustrate the interior construction and arrangement; and

Fig. 3 is a top or plan view of the apparatus shown in Fig. 1, also partly broken away to illustrate the interior construction and arrangement.

It should of course be understood that the description and drawing herein are illustrative merely, and that various changes and modifications may be made in the structure disclosed without departing from the spirit of the invention.

Referring to the drawing, in the particular embodiment of the invention therein shown, 4 is a cabinet, the interior of which provides a chamber 5 within which the garments are subjected to the process as is hereinafter more fully set

2

forth. At one end of the cabinet 4 is a door 6 providing access to the internal chamber 5 of the cabinet 4. A plurality of steam pipes 7 are horizontally disposed in the bottom of the chamber 5, and live steam is supplied thereto from a supply pipe 8 and the supply is controlled by a stop valve 9 provided in said pipe line 8. The pipes 7 are provided with a plurality of jet openings 10 so arranged as to project the steam upwardly when the same is permitted to flow from the supply pipe 8. A main control valve 11 is also mounted in the pipe 8, and between the valves 9 and 11 there is a branch pipe 12 extending from the pipe line 8 to an air heater 13. The air heater 13 is auxiliary to a blower 14 the fan vanes 15 of which are actuated by an electric motor 16. The air is pumped by the vanes 15 of the blower 14 into the cabinet chamber 5 whenever the motor 16 is operated. The motor 16 is controlled by a suitable switch 17 arranged on the side of the cabinet in a position adjacent the valve 9 for the convenience of the operator in the control of the apparatus.

The top of the cabinet is provided with an inclined roof 18, so that any water of condensation, which may accumulate thereon, will be carried to the side of the cabinet and pass harmlessly to the bottom where the same may be drained off by an outlet pipe 19, along with any other water of condensation which may accumulate in the bottom of the chamber.

Extending upwardly from the inclined roof 18 of the cabinet 4 is an outlet or vent pipe 19 which serves to prevent any accumulation of pressure within the chamber 5, and also permits the heated air from the blower 14 to be exhausted from the cabinet to carry away any of the moisture which may have been taken up by the previously steamed garments.

The garments are individually mounted on coat hangers 20 of the well known and common type, being suspended by means of said coat hangers on the top rod or bar 21 of a truck or carriage 22. The truck or carriage 22 is provided with suitable wheels 23, to facilitate the handling of the garments which are suspended by the hangers 20 from the top rod or bar 21 thereof. The truck is provided with a handle structure 24 by means of which it may be readily manipulated to move it into and out of the chamber 5 of the cabinet 4.

The method of the present invention and the use of the above described structure will now be explained.

The garments, having been first placed upon the coat hangers 20, are then suspended by means

of said coat hangers from the top bar 21 of the truck or carriage 22. The truck or carriage is then pushed into the interior chamber 5 of the cabinet 4 and the door 6 is closed. The main steam valve 11 is then opened, as is also the valve 9, whereupon the live steam will flow through the pipes 7 in the bottom of the chamber 5, and the live steam will be projected upwardly from the jet apertures 10 into the bottom openings of the garments which are suspended from the top bar 21 of the truck, thereby causing the garments to be distended and permitting the steam to pass through the fabric of the garments.

The steam used is preferably of a temperature whereby a relatively small quantity of same will be condensed on the fibers of the fabric, and most of the steam will pass off through the flue 19 which extends upwardly from the roof 18 of the cabinet. However there may be some incidental condensation of the steam on the side walls of the cabinet 4 as well as on the under side of the roof 18 thereof. The water of condensation which accumulates on the top and sides of the cabinet will pass downwardly to the bottom of the cabinet and will thence be drained off through the pipe 29 provided at the bottom thereof.

While steam is being supplied to the jet pipes 7 in the bottom of the chamber 5 a portion of the same will be passing to the heater 13, and serve to heat the air which is supplied therethrough to the blower 14. However, the blower 14 is not ordinarily actuated while the steam is being supplied to the discharge pipes 7 and after the garments have been subjected to the action of the steam for a sufficient length of time the valve 9 is closed thus cutting off further supply of steam to the pipes 7.

The switch 17 may now be operated to cause the motor 16 to actuate the vanes 15 of the blower 14 and thereby pump dry heated air into the interior of the chamber 5. It should be noted that the blower is arranged near one end of the cabinet 4 and that the outlet flue 19 is arranged at the other end thereof so that there will be an induced circulation of dry heated air through the chamber 5 of the cabinet which will take up any residual moisture within the garments and carry the same up through the flue 19.

By the foregoing arrangement there is provided a simple, efficient, and relatively inexpensive apparatus by means of which large numbers of garments may be finished rapidly and expeditiously without necessitating the individual pressing of the same, resulting in a considerable saving of labor for finishing the garments in a satisfactory condition.

I claim:

1. The method of simultaneously finishing a plurality of garments which comprises subjecting said garments in a closed chamber to the action of steam projected upwardly from below said garments whereby a portion thereof will pass directly into the bottom openings of said garments thereby to distend the same and to permeate the fabrics thereof with the steam, and thereafter subjecting said garments without moving the same from or in said chamber to the action of dry heated air to remove any residual moisture remaining in the garments.

2. The method of simultaneously finishing a plurality of garments which comprises subjecting said garments in a closed chamber to the action of steam projected upwardly whereby a por-

tion of the same will pass directly into the bottom openings of the garments thereby to distend the same and to permeate the fabrics thereof with the steam, and immediately thereafter subjecting said garments while still in said chamber to the action of dry heated air to remove any residual moisture remaining in the garments.

3. The method of simultaneously finishing a plurality of garments which comprises suspending said garments side by side in a closed chamber and then subjecting them to the action of steam projected upwardly whereby a portion of the same will pass directly into the bottom openings of the garments thereby to distend the same and to permeate the fabrics thereof with the steam, and immediately thereafter subjecting said garments, without disturbing the same or removing them from the chamber, to the action of dry heated air.

20 4. Apparatus for simultaneously finishing a plurality of garments comprising a closed cabinet having an internal chamber, portable means for suspending the garments side by side in said chamber in close proximity to each other, means disposed in the bottom of the chamber for projecting steam upwardly directly into the bottom openings of the garments thereby to distend the garments and to permeate the fabrics thereof with the steam, and means for projecting dry heated air into the chamber to circulate the same through and about the garments while they are in the chamber.

5. Apparatus for simultaneously finishing a plurality of garments comprising a closed cabinet having an internal chamber, portable means for suspending the garments side by side in said chamber in close proximity to each other, means disposed in the bottom of the chamber for projecting steam upwardly directly into the bottom openings of the garments thereby to distend the garments and to permeate the fabrics thereof with the steam, a blower for projecting air into the chamber to circulate the same through and about the garments in the chamber and means for heating the air which is projected into the chamber by the blower.

6. Apparatus for simultaneously finishing a plurality of garments comprising a closed cabinet having an internal chamber, portable means for supporting the garments side by side in said chamber in close proximity to each other, means disposed in the bottom of the chamber for projecting steam upwardly directly into the bottom openings of the garments thereby to distend the garments and to permeate the fabrics thereof with the steam, a flue extending from the top of the chamber near one end thereof, a blower for projecting air into the chamber at the other end thereof, and means for heating the air which is projected into the chamber by the blower.

7. Apparatus for simultaneously finishing a plurality of garments comprising a closed cabinet having an internal chamber, portable means for supporting the garments side by side in said chamber in close proximity to each other, a plurality of steam pipes disposed in the bottom of the chamber and having outlets for projecting steam upwardly directly into the bottom openings of the garments thereby to distend the garments and to permeate the fabrics thereof with the steam, a flue extending from the top of the chamber near one end thereof, a blower for projecting air into the chamber at the other end thereof, and means for heating the air which is projected into the chamber by the blower.

8. Apparatus for simultaneously finishing a plurality of garments comprising a closed cabinet having an internal chamber, a wheeled truck having a top member from which the garments are suspended side by side in close proximity, means disposed in the bottom of the chamber for projecting steam upwardly directly into the bottom openings of the garments thereby to distend the garments carried by the truck and to permeate the fabrics thereof with the steam, and means for projecting dry heated air into the chamber.

9. Apparatus for simultaneously finishing a plurality of garments comprising a closed cabinet having an internal chamber, a wheeled truck having a top member from which the garments are suspended side by side in close proximity, means disposed in the bottom of the chamber for projecting steam upwardly directly into the bottom openings of the garments thereby to distend the garments carried by the truck and to permeate the fabrics thereof with the steam, a blower for projecting air into the chamber, and means for heating the air which is projected into the chamber by the blower.

10. Apparatus for simultaneously finishing a plurality of garments comprising a closed cabinet having an internal chamber, a wheeled truck having a top member from which the garments are suspended side by side in close proximity, means disposed in the bottom of the chamber for projecting steam upwardly directly into the bottom openings of the garments thereby to distend the garments carried by the truck and to permeate the fabrics thereof with the steam, a flue extending from the top of the chamber near one end thereof, a blower for projecting air into the chamber at the other end thereof, and means for heating the air which is projected into the chamber by the blower.

11. Apparatus for simultaneously finishing a plurality of garments comprising a closed cabinet having an internal chamber, a wheeled truck having a top member from which the garments are suspended side by side in close proximity, a door at one end of the cabinet whereby the truck with the garments carried thereby may be

placed in and removed from the chamber, means disposed in the bottom of the chamber for projecting steam upwardly directly into the bottom openings of the garments thereby to distend the garments carried by the truck and to permeate the fabrics thereof with the steam, a flue extending from the top of the chamber near one end thereof, a blower for projecting air into the chamber at the other end thereof, and means for heating the air which is projected into the chamber by the blower.

12. Apparatus for simultaneously finishing a plurality of garments comprising a closed cabinet having an internal chamber, a wheeled truck having a top member from which the garments are suspended side by side in close proximity, a door at one end of the cabinet whereby the truck with the garments carried thereby may be placed in and removed from the chamber, a plurality of steam pipes disposed in the bottom of the chamber and having outlets for projecting steam upwardly directly into the bottom openings of the garments thereby to distend the garments carried by the truck and to permeate the fabrics thereof with the steam, a flue extending from the top of the chamber near one end thereof, a blower for projecting air into the chamber at the other end thereof, and means for heating the air which is projected into the chamber by the blower.
